US00D947628S

(12) **United States Design Patent** (10) **Patent No.:** **US D947,628 S**
(45) **Date of Patent:** **** Apr. 5, 2022**

(54) **WRENCH**

(71) Applicant: **Klein Tools, Inc.**, Lincolnshire, IL (US)

(72) Inventors: **Johnnie M. Coats**, Lincolnshire, IL (US); **Daniel R. Pearson**, Lincolnshire, IL (US)

(73) Assignee: **Klein Tools, Inc.**, Lincolnshire, IL (US)

(**) Term: **15 Years**

(21) Appl. No.: **29/691,129**

(22) Filed: **May 14, 2019**

(51) LOC (13) Cl. **08-05**

(52) U.S. Cl.

USPC **D8/21**; D8/25

(58) **Field of Classification Search**

(57) **CLAIM**

The ornamental design for a wrench, as shown and described.

DESCRIPTION

FIG. 1 is a right front side perspective view of a wrench in accordance with our new design;

FIG. 2 is a front orthogonal view of the wrench shown in FIG. 1;

FIG. 3 is a rear orthogonal view of the wrench shown in FIG. 1;

FIG. 4 is a bottom orthogonal view of the wrench shown in FIG. 1;

FIG. 5 is a top orthogonal view of the wrench shown in FIG. 1;

FIG. 6 is a right side orthogonal view of the wrench shown in FIG. 1;

FIG. 7 is a left side orthogonal view of the wrench shown in FIG. 1; and,

FIG. 8 is a right rear side perspective view of the wrench shown in FIG. 1.

The broken lines shown are included for the purpose of illustrating portions of the wrench that form no part of the claim.

1 Claim, 8 Drawing Sheets
